CONTROL MECHANISM FOR PRESSES

Elbert L. Hyde, Shaker Heights, Ohio, assignor to
 The American Laundry Machinery Company,
 Norwood, Ohio, a corporation of Ohio

Application September 3, 1937, Serial No. 162,292

5 Claims. (Cl. 192—131)

This invention relates to improvements in control mechanism for pressing machines.

One of the objects of the present invention is to provide in a power closed pressing machine control means for the power means which is actuated by spaced safety manuals having two stages of operation. These manuals are arranged in their first stage of operation to actuate the control means for a press closing operation, but so arranged that upon release of either manual the press will open. A maintaining means for holding the press closed is provided and operable by second stage operation of the manuals. One of the features of the present invention is the provision of an enabling block without which the second stage of manual operation is ineffective to establish the maintaining means. This block is arranged for movement into enabling position upon the press reaching a safe closed position where the operator's hand cannot be caught between the pressing elements and injured.

Several modifications of my invention are disclosed. In one form the two stages of manual operation occur in the same direction. In the second form the two stages occur in directions at angles to each other, and in a third form the two stages of operation occur in opposite directions.

The various novel features of my invention are more fully shown in the accompanying drawings and description and the essential features will be set forth in the claims.

In the drawings, Fig. 1 shows an end elevation of a pressing machine in open position with one form of my improved control mechanism shown diagrammatically; Fig. 2 is a view of the press of Fig. 1 after the same has reached a safe closed position with the control mechanism diagrammatically shown in corresponding position; Fig. 3 is a view of the control mechanism of Figs. 1 and 2, showing the parts in fully actuated position; Figs. 4 to 7 show a modified form where the second stage of manual operation is in the opposite direction to the first; Figs. 4, 5 and 6 correspond respectively to open, safe closed and fully closed positions as in Figs. 1 to 3; Fig. 7 is an elevational view taken approximately on the line 7—7 of Fig. 4; Figs. 8 to 11 show a third modification where one of the manuals has a second stage of operation at an angle to its first stage of operation; Figs. 8, 9 and 10 are diagrammatic views of control mechanism analogous to those shown in connection with the previous modifications, that is, Fig. 8 corresponds to press open position, Fig. 9 to safe closed position, and Fig. 10 to fully closed position of the press; while Fig.

11 is a plan view of the control mechanism of Fig. 8.

While my invention is applicable to various types of pressing machines, I have illustrated the same as applied to a type of press commonly found in garment and laundry presses having a frame 12 supporting a pressing bed 13 and also supporting a yoke 14 which carries a pressing head 15 into and out of engagement with bed 13 upon manipulation of the toggle 16 by the fluid motor 17. A spring 18 tends to return the head to open position. Fluid supply for motor 17 is by way of conduits 19 and 20 valve casing 21 and conduit 22. Casing 21 houses a normally closed inlet valve 21a and a normally open outlet valve 21b on a stem 21c which is provided with a yieldable end 21d and with a shoulder 21e. Valves in casing 21 are actuated by means of the floating whiffletree 23, the opposite ends of which are engageable by pins 24 and 25 connected with the manually operated push buttons 26 and 27 respectively. Each button has two stages of operation. During the first stage the springs 28 are not compressed until the collars 29 hit the shoulders 30. Following this a second stage movement occurs upon compression of springs 28. First stage movement is sufficient to actuate the valves in casing 21, but because of the whiffletree arrangement both buttons must be coincidentally depressed. If either of the buttons is released the valves in casing 21 return to unactuated position and the press will open. For maintaining the press closed means is provided for holding the valves in casing 21 in operated position. The pin 24 connected with manual 26 is adapted to actuate the valves in casing 31 for this purpose, but such actuation of pin 24 is ineffective to establish the maintaining means until the press is safe closed because of the air gap 32. To fill this gap a block 33 is suitably supported and pivotally connected with a rod 34 which in turn is connected with a press part, in the present instance the toggle 16. The block 33 has a narrow portion 33a normally lying over the valve stem for the valves in casing 31 and a wide portion 33b which is the enabling portion of the block.

In casing 31 is a normally closed inlet valve 31a and a normally open outlet valve 31b both actuated by stem 31c, which has a shoulder 31d. Upon the actuation of the valves in casing 31 motive fluid is supplied through conduit 19, casing 31 and conduits 35, 36 and 37 to the diaphragm servo motors 38 and 39. Servo motor 38, when energized, acts through lever 40 against shoulder 31d to hold the valves in casing 31 in actuated

position. Motor 39, when energized, acts through lever 41 against shoulder 21e to hold the valves in casing 21 in actuated position. A conduit 42 leads to casing 43, which houses a normally closed outlet valve 43a operable by stem 43b.

With the press in the open position of Fig. 1, the operator arranges the lay of work on bed 13 and depresses manuals 26 and 27 through the first stage of their operation. This moves the valves in casing 21 to actuated position, supplying motive fluid to motor 17 and moving the press to closed position. The press, however, will not remain closed unless the maintaining means is actuated. Upon the press reaching the safe closed position of Fig. 2, the wide portion 33b of block 33 comes between valve stem 31c and the pin 24 connected with button 26. Second stage movement of buttons 26 and 27 (permitted by the yielding end 21d of valve stem 21c) actuates the valves in casing 31 to their operated position as shown in Fig. 3. This supplies motive fluid to servo motors 38 and 39, thus holding the valves in casing 31 and 21 in actuated position as shown in Fig. 3, whereupon the buttons 25 may be released and the press will remain closed. To open the press valve stem 43b is momentarily depressed, evacuating the maintaining servo motors 38 and 39, permitting the press to open.

While in this form of control second stage movement of buttons 26 and 27 is always possible, no maintaining effect will be produced as the valves in casing 31 cannot be actuated until the wide portion of block 33 is in the position of Figs. 2 and 3. If the buttons 26 and 27 are moved through both stages of operation upon their first actuation, the press will close, however, because the wedge shape of block 33 permits this block to be pulled from the position of Fig. 1 to that of Figs. 2 and 3, while the operator holds the manuals depressed.

In the modification of Figs. 4 to 7, the control mechanism functions similarly to that just described, but the second stage of manual operation is in the opposite direction to the first. In Fig. 4 the pressing machine is shown in the open position and control for supply of motive fluid to motor 17 is here of a slightly different form, namely, the valves in casings 44 and 45 must both be held in actuated position to effectively supply fluid to motor 17. This is in place of the whiffle-tree arrangement of Figs. 1 to 3. Valve casing 44 uses a normally closed inlet valve 44a and a normally open outlet valve 44b on a common stem 44c having a yieldable end 44d and a shoulder 44e. Casing 45 houses a normally open outlet valve 45a on a stem 45b having a shoulder 45c. Manuals 46 and 47 serve to actuate the valves in casings 44 and 45 respectively and these manuals are so spaced as to require a hand of the operator on each of them for their coincidental operation. It is obvious that if both sets of valves are not actuated at once fluid cannot be effectively supplied to motor 17. The first stage of manual operation is downwardly and serves to move the valves in casings 44 and 45 to actuated position.

The second stage of manual operation, at least with respect to manual 46, is upwardly and serves to establish the maintaining means for holding the valves in casings 44 and 45 in actuated position. The mechanism shown for this purpose comprises a slide 48 suitably mounted in the press frame for reciprocation and provided with a catch 49 connected by suitable linkage with a catch release handle 50 and spring means 51 for main-

taining the catch in its extended position. Located above the slide 48 is a valve casing 52 housing a normally closed inlet valve 52a and a normally open outlet valve 52b on stem 52c which is provided with a shoulder 52d. An air gap 53 between slide 48 and valve stem 52c normally prevents upward movement of slide 48 from actuating the valves in casing 52. A block 54 suitably mounted for reciprocation is pivotally connected by rod 55 with the press toggle 16. When the press reaches safe closed position the straightened toggle moves block 54 from the position of Fig. 4 to the position of Figs. 5 and 6, thus enabling the upward movement of slide 48 to actuate the valves in casing 52.

Operation of the valves in casing 52 supplies motive fluid from conduit 56 through conduit 57, casing 52, and conduits 58, 59, 60 and 61 to servo motors 62, 63 and 64. Motor 62, when energized, acts through lever 65 to hold the valves in casing 52 in actuated position. Motor 63 acts through lever 66 to hold the valve in casing 45 in actuated position. Motor 64, through lever 67, will hold the valves in casing 44 in actuated position. Conduit 68 leads to casing 69, which houses a normally closed outlet valve 69a operable by stem 69b.

The operation of this modified form is as follows:

With the press in the open position, the operator depresses manuals 46 and 47, which moves the valves in casing 44 and 45 to supply motive fluid through conduit 56, casing 44 and conduits 70 and 71 to motor 17. The first stage of manual operation carries the manuals to the position of Fig. 5 where manual 46 engages beneath catch 49 on slide 48. Until the press is safe closed, release of manual 46 or 47 will open the press. Release of manual 47 exhausts pressure from motor 17, as will be obvious. Release of manual 46 will cause the same to move upwardly under the influence of its spring, returning the valves in casing 44 to their unactuated position, and while it may move the slide 48 upwardly, yet because of the gap 53 no maintaining effect will be produced. However, when the press is safe closed, block 54 moves into the position of Figs. 5 and 6, whereupon release of manual 46 causes the same to be moved upwardly by its spring, as shown in Fig. 6. This carries slide 48 upwardly and through block 54 actuates the valves in casing 52 to the position of Fig. 6, energizing servo motors 62, 63 and 64 and holding all of the associated valves in operated position. The press will thus remain closed and the manuals may be released. To open the press valve stem 69b is momentarily depressed, evacuating all of the maintaining servo motors. Also release handle 50 must be actuated to release catch 49 whereupon slide 48 will return to its lower position ready for the next operation.

It will be noted in comparing the yieldable valve stem end 44d in Figs. 4 and 5, that the spring of this yieldable end is compressed before manual 46 engages beneath catch 49. Therefore, during second stage movement of manual 46 upwardly, the valves in casing 44 are not released but remain in actuated position until the valves in casing 52 are actuated to establish the maintaining effect of servo motor 64.

In the modification of Figs. 8 to 11, one of the manuals is given a second stage of operation at 70 an angle to its first stage of operation. It will be understood that the control mechanism of these drawings is intended for use in connection with the press of previous modifications, which press will have an operating motor 17. The supply of 75

fluid to this motor is similar to that described in connection with Figs. 4 to 7, that is to say, these same valves in casing 44 and casing 45 must be operated by manuals 72 and 73 to supply motive fluid to motor 17. Here, however, the valves in casing 52 are placed to one side of manual 72 instead of above the manual as in Figs. 4 to 7. The valves, however, operate the same and are given the same reference numbers as are all other parts having similar functions.

It will be noted that manual 72 is urged upwardly by spring 74 and toward the left, as viewed in Figs. 8 to 10, by spring 75. This manual operates in an L-shaped slot 76 in the press frame. The first stage of manual movement is downwardly from the position of Fig. 8 to that of Fig. 9. This actuates the valves in casing 44. The second stage of operation of manual 72 is toward the right, as viewed in the various figures from the position of Fig. 9 to that of Fig. 10. This movement is ineffective to actuate the valves in casing 52 unless the block 54 is in the position of Figs. 9 and 10. This block is in all respects analogous to block 54 described previously, and is connected with the press parts so as to be moved from the normal position of Fig. 8 when the press is open to the position of Figs. 9 and 10 when the press is safely closed.

It is thought the operation of this form of the device will be understood. When the press is open manuals 72 and 73 are in the position of Fig. 8 and are then depressed to the position of Fig. 9. This actuates the valves in casings 44 and 45, as shown, and supplies motive fluid to the motor 17. If either of the manuals is released at this time, the press will open. Second stage manual operation of manual 72 from the position of Fig. 9 to that of Fig. 10 is effective to establish the maintaining means if the press is safely closed so that block 54 is in the position of Fig. 10. In this figure it will be noted that movement of manual 72 to the right has moved the valves in casing 52 to their actuated position, thus supplying motive fluid to the servo motors 62, 63 and 64 so as to hold the valves in casings 52, 45 and 44 respectively in their actuated positions. The press will then remain closed until the release valve 69a is opened.

It will be noted that in all forms of the device, second stage operation of one or more of the manuals is ineffective to set the maintaining means unless the press has safely closed, moving an enabling block into proper position.

What I claim is:

1. In a pressing machine having coacting relatively movable pressing members and power actuated operating mechanism therefor, a control member for causing press closing action of said mechanism, a control member for maintaining said press closed, manual means having first and second stages of operation for actuation of said first and second named control members respectively, there being an operative connection between said manual means in its first stage of operation and said first named control member requiring coincidental use of both hands of the operator on said manual means for effective operation of the said control member, there being a relationship between said manual means in its second stage of operation and said second named control member including an air gap normally rendering said manual means inoperative to actuate the said member, a gap-filling block for enabling operation of said second named control member, said block being in inoperative position

when said press is open, means for moving said block to enabling position by movement of said pressing members to safe-closed position, and one of said control members being movable to inoperative position for causing the press to open.

2. In a pressing machine having coacting relatively movable pressing members and power actuated operating mechanism therefor, a control member for causing press-closing action of said mechanism, a control member for maintaining said press closed, manual means having first and second stages of operative movement for actuation of said first and second named control members respectively, said second stage movement being in the same general direction as said first stage, there being an operative connection between said manual means in its first stage of operation and said first named control member requiring coincidental use of both hands of the operator on said manual means for effective operation of the said control member, there being a relationship between said manual means in its second stage of operation and said second named control member including an air gap normally rendering said manual means inoperative to actuate the said member, a gap-filling block for enabling operation of said second named control member, said block being in inoperative position when said press is open, means for moving said block to enabling position by movement of said pressing members to safe-closed position, and one of said control members being movable to inoperative position for causing the press to open.

3. In a pressing machine having coacting relatively movable pressing members and power actuated operating mechanism therefor, a control member for causing press-closing action of said mechanism, a control member for maintaining said press closed, manual means having first and second stages of operative movement for actuation of said first and second named control members respectively, said second stage movement being in the opposite direction to said first stage, there being an operative connection between said manual means in its first stage of operation and said first named control member requiring coincidental use of both hands of the operator on said manual means for effective operation of the said control member, there being a relationship between said manual means in its second stage of operation and said second named control member including an air gap normally rendering said manual means inoperative to actuate the said member, a gap-filling block for enabling operation of said second named control member, said block being in inoperative position when said press is open, means for moving said block to enabling position by movement of said pressing members to safe-closed position, and one of said control members being movable to inoperative position for causing the press to open.

4. In a pressing machine having coacting relatively movable pressing members and power actuated operating mechanism therefor, a control member for causing press-closing action of said mechanism, a control member for maintaining said press closed, manual means having first and second stages of operative movement for actuation of said first and second named control members respectively, said second stage movement being in a lateral direction relative to said first stage, there being an operative connection between said manual means in its first stage of operation and said first named control member requiring coincidental use of both hands of the

- operator on said manual means for effective operation of the said control member, there being a relationship between said manual means in its second stage of operation and said second named control member including an air gap normally rendering said manual means inoperative to actuate the said member, a gap-filling block for enabling operation of said second named control member, said block being in inoperative position when said press is open, means for moving said block to enabling position by movement of said pressing members to safe-closed position, and one of said control members being movable to inoperative position for causing the press to open.
5. In a pressing machine having coacting relatively movable pressing members and power actuated operating mechanism therefor, control means for said mechanism normally in power

cut-off position, power means for holding said control means in power-supply position, two-hand safety manual means for moving said control means to power-supply position, said manual means having an additional movement other than that necessary to actuate said control means, a block movable by said additional movement of said manual means, said block normally being in inoperative position where it is not movable by said manual means, means for moving said block to operative position when said pressing members reach safe-closed position, a control member for supplying power to said power means, said control member being positioned for actuation by manual movement of said block, and said control member being movable to inoperative position for causing opening of said press.

ELBERT L. HYDE.
